UNITED STATES PATENT OFFICE.

GEORGE COWLEY BINGHAM, OF MALDON, ENGLAND, ASSIGNOR OF ONE-HALF TO
EDMUND ERNEST BENTALL, OF MALDON, ENGLAND.

LIQUID-FUEL INTERNAL-COMBUSTION ENGINE.

1,410,241.

Specification of Letters Patent. Patented Mar. 21, 1922.

Application filed December 19, 1921. Serial No. 523,422.

To all whom it may concern:

Be it known that I, GEORGE COWLEY BINGHAM, a subject of the King of England, residing at 34 London Road, Maldon, in the county of Essex, England, have invented new and useful Improvements in Liquid-Fuel Internal-Combustion Engines, of which the following is a specification.

My invention relates to that class of engine wherein the charge is fired by heat of compression, and it has for its object to so effect the supply of fuel to the working cylinder that pre-ignition is rendered impossible.

With this object I compress exhaust gases and utilize these to convey the fuel charge to the working cylinder at the end of the compression stroke; these exhaust gases being compressed to such a degree that they will cause ignition by the heat of their compression immediately the fuel enters the main cylinder and mixes with the air therein.

My invention is therefore applicable to both high and low compression engines, that is to say to those wherein the charge is compressed in the main cylinder to a sufficient extent as to cause ignition by the heat of its compression, when the fuel charge is injected, and to those wherein the compression in the main cylinder is not so high; ignition in the latter case being caused solely by the heat of compression of the exhaust gases.

For this purpose I prefer to employ an auxiliary cylinder, having a piston working therein operated from the main engine shaft or otherwise, and provided with an inlet for the exhaust gases from the main cylinder, and an outlet communicating with the main engine cylinder through a passage or chamber into which the oil fuel is drawn or forced; said inlet and outlet being suitably governed.

With such an arrangement air will be drawn into the main cylinder in the usual manner at the suction stroke, and simultaneously exhaust gases into the auxiliary cylinder, and oil fuel into the passage or chamber between the main and auxiliary cylinders.

At the end of the compression stroke in both cylinders the exhaust gases in the auxiliary cylinder will have attained a sufficient

pressure by simple compression to cause a supply of fuel to be forced into the main cylinder, when said communication between the two cylinders is opened, when it will mix with the air therein and be fired by the heat of compression.

In the accompanying drawings I have illustrated how my invention may be carried into practical effect, and, although not necessarily limited thereto, I will further describe the same by the aid of such drawings.

Of these drawings Figures 1. and 2. are sectional plans of the main portions of the cylinders of two four stroke engines of slightly different forms constructed according to my invention, and wherein the auxiliary cylinder and its piston extend from the main cylinder and piston, while Figures 3. and 4. are sections at lines X—X and Y—Y of Figures 1. and 2. of plans of the engines.

Figure 5. is a sectional elevation of the main portions of the cylinders of a four stroke engine wherein the auxiliary cylinder is arranged parallel to the main cylinder and the connection between the two for the passage of the exhaust gases is through a passage extending from the main engine cylinder exhaust.

All of these engines are designed to work on high compression, but it will be obvious that with little modification they could be adapted to work on low compression.

In the construction shewn in Figures 1. and 3. A. is the main engine cylinder, which is fitted with the usual inlet and outlet valves, and B. is the auxiliary cylinder, which forms a continuation of the main cylinder, and its piston C. forms a continuation of the main engine piston D. This auxiliary cylinder is provided with an inlet E. for exhaust gases, controlled by a valve F. and provided with an oil fuel inlet E¹, and an outlet G. which communicates through tube H. and passages K. (Figure 3) with the main cylinder.

This communication is controlled by the valve L., which is suitably operated from the engine to open at the end of the compression stroke of each cycle of the engine, while the passages K. also communicate with the liquid fuel supply through the non-return valve M. (Figure 3).

An engine so constructed would operate as follows:—

During the suction stroke of the two pistons air will be drawn into the main cylinder and exhaust gases into the auxiliary cylinder, and simultaneously a supply of liquid fuel will pass into the passages K, where it will remain owing to the shape (as shewn) of said passages.

10 At the end of the compression stroke of the two pistons the valve L. will open and the compressed exhaust gases in the auxiliary cylinder will pass through the tube H. and passages K. into the main cylinder taking with them the oil fuel in the passages K. which will be fired by the heat of compression immediately it mixes with the air in the main cylinder.

15 On the exhaust stroke the valve L. will not open so that the exhaust gases drawn into the auxiliary cylinder during the power stroke of the main engine piston will be compressed and held and will expand during the suction stroke of the main engine piston 20 and be recompressed during the compression stroke of the latter, when the cycle will be repeated.

25 At the commencement of working the auxiliary cylinder will be charged with air 30 and this may be utilized to convey the oil fuel to the main cylinder or the valve E² may be opened to allow oil fuel to mix with the air entering through E. so that an explosive charge will be fired by the heat of compression in the auxiliary cylinder and the resulting gases utilized to force the fuel supply into the main cylinder.

35 The construction shewn in Figures 2. and 40 is the same as that shewn in Figures 1. and 3. so far as concerns the arrangement of the main and auxiliary cylinders and pistons and their operation, but the communication between the two cylinders is effected through by-passages N., to which the 45 oil fuel is supplied once only during each engine cycle, and passages O. through the auxiliary piston, which latter consequently acts as a control valve seeing that the passages N. and O. can only communicate with 50 one another when the auxiliary piston occupies such a position that the ends of these passages register.

55 An engine of either of the above types may obviously be adapted to work on the two stroke cycle if desired.

60 In the modified construction shewn in Figure 5. the main cylinder A. and the auxiliary cylinder B. are arranged parallel to one another, and their pistons C. and D. operate in unison. The auxiliary cylinder is provided with an inlet E. connected to the main cylinder and controlled by a valve F. communicating through passages O. controlled by valve L., with the main cylinder

and with which the oil supply inlet P. also 65 communicates.

With this particular construction the cycle of operations is the same as with the construction shewn in Figures 1. and 3. but where desired the auxiliary piston may be 70 operated through suitable gear so that it makes one reciprocation to two of the main piston.

75 In this engine the fuel is pumped to the passages, through which the compressed exhaust gases pass from the auxiliary to the main cylinder, by a suitable pump.

80 From the foregoing description it will be obvious that with little modification, in the case of four stroke engines, a non-return valve or the equivalent may be introduced into the passage between the two cylinders so that two charges of exhaust gases may be compressed in said passage at each engine cycle, to ensure a sufficiency as regards both 85 quantity and pressure to carry the oil fuel into the main cylinder.

Having now particularly described and ascertained the nature of my said invention and in what manner the same is to be performed, I declare that what I claim is:—

90 1. A liquid fuel internal combustion engine including a main cylinder, an auxiliary cylinder, a passage connecting the auxiliary cylinder with the exhaust passage of the 95 main cylinder for conducting exhaust gases into the auxiliary cylinder to enable the same to be compressed therein and a separate passage connecting the auxiliary cylinder with the main cylinder and into which the fuel 100 charge is delivered to cause the compressed exhaust gases to carry the said charge into the main cylinder and fire the charge by heat of compression of the exhaust gases.

105 2. A liquid fuel internal combustion engine including a main cylinder, an auxiliary cylinder, a passage connecting the auxiliary cylinder with the main cylinder and arranged to conduct the exhaust gases from the main cylinder to the auxiliary cylinder, 110 said gases being compressed within the auxiliary cylinder for firing the engine by heat of compression of said gases, a separate passage connecting the auxiliary cylinder with the main cylinder and into which latter passage the fuel charge is fed whereby the fuel 115 charge will be carried into the main cylinder by the compressed exhaust gases from the auxiliary cylinder, and means for introducing an explosive charge into the auxiliary 120 cylinder for firing the same when starting up the engine to utilize the gases generated in the auxiliary cylinder to convey the first fuel charge to the main cylinder.

125 In testimony whereof I have signed my name to this specification.

GEORGE COWLEY BINGHAM.
